(57) **CLAIM**

The ornamental design for a solar driveway light, as shown and described.

DESCRIPTION

FIG. 1 is a perspective view of a solar driveway light showing my new design;

FIG. 2 is another perspective view thereof;

FIG. 3 is a front elevational view thereof, the rear elevational view, the left elevational view and the right side view are identical;

FIG. 4 is a top side view thereof; and,

FIG. 5 is a bottom plan view thereof.

The broken lines in the figures are for the purposes of illustrating portions of the solar driveway light, which form no part of the claimed design.
